UNITED STATES PATENT OFFICE.

RICHARD CORNELIUS ELLIOTT, OF LONDON, ENGLAND, ASSIGNOR TO LANSTON MONO-TYPE MACHINE COMPANY, OF PHILADELPHIA, PENNSYLVANIA, A CORPORATION OF VIRGINIA.

AUTOMATIC TYPOGRAPHIC OR TYPE CASTING AND COMPOSING MACHINE.

Application filed January 19, 1923. Serial No. 613,756.

To all whom it may concern:

Be it known that I, RICHARD CORNELIUS ELLIOTT, a British subject, and a resident of 86 St. George's Square, Pimlico, London, S. W., England, have invented certain new and useful Improvements in Automatic Typographic or Type Casting and Composing Machines; and I do hereby declare the following to be a full, clear, and exact description of the same, reference being had to the accompanying drawings, forming part of this specification, and to the characters of reference marked thereon.

This invention relates to typographic or type casting and composing machines which are controlled by previously prepared patterns, record strips or controllers.

The pattern is usually in the form of a strip or ribbon of paper in which a series or succession of different combinations of signals are formed by punches.

A pattern preparing machine of the kind referred to is exemplified in the commercial product of Lanston Monotype Machine Company, and its basic principles are well-known and are shown, for example, in United States Letters Patent 944,405, dated December 28, 1909.

The chief function of the signals of the pattern is to control the operations of a type casting and composing machine which is provided with a die case containing matrices arranged in columns and rows running in two directions at right angles to each other, and with positioning mechanism responsive to these signals to effect a two-way movement of the die case, and thereby select the individual matrix from which a cast is to be made.

A casting machine adapted to be controlled by a pattern such as may be produced with the aid of the patented keyboard machine already referred to, is equally well-known and is shown, for example, in United States Letters Patent 625,998, dated May 30, 1899. In such machine or the commercial improvement thereof, the positioning mechanism comprises two series of record strip controlled gages or stop pins each representing progressing adjustments of the die case in one direction.

The record strip perforations act as valves or the like in a pneumatic system, and as the

record strip is passed through an interpreting position of the casting machine by a step by step motion, the perforations in the strip uncover ports which allow air under pressure to pass directly to the stop pins, the ports leading to which have been uncovered so that these pins are projected and act as gages for the die case positioning mechanism. Each perforation controls only one stop pin and each stop pin controls one position of the die case in one direction of its movement. With this arrangement, in order to position each of the two hundred twenty-five matrices which the die case usually contains, there are provided two series of stop pins, each series having fifteen pins. In addition to these designating perforations, three other perforations controlling justification mechanism must be accommodated in the record strip, so the strip is therefore of such dimension as to extend over thirty-one ports.

An object of the present invention is to provide mechanism such that the functions performed by the perforations in the record strip can be increased considerably or the functions hitherto performed can be performed by a record strip of considerably decreased dimensions.

In accordance with the present invention, there are provided two series of motors or pneumatic pistons, one series for each series of stop pins, and these motors are controlled by the perforations in the record strip: each motor in turn controls a series of valves which have intercommunicating conduits or passages and control the admission, to the pistons of the stop pins, of an independent constant air supply. All the valves of a series are operated simultaneously when the motor connected thereto is energized by a perforation in the record strip and the valves are operated in various combinations to produce the operation of the correct stop pin.

As applied to a machine having two series of stop pins with fifteen pins in each series, two series of four motors in each are sufficient to operate all the pins in each series, and these motors can be operated singly or in various combinations. Thus a record strip only wide enough to accommodate two series of four designating perforations each, eight in all, with the three justification perfor-

tions, making eleven perforations in all in a line, can be employed instead of the usual thirty-one perforations.

Referring to the accompanying drawings:

Fig. 1 is a partially diagrammatic view showing a portion of the patented type casting and composing machine above referred to and embodying the present invention.

10 Fig. 2 is an elevation of part of such machine.

Fig. 3 is a sectional elevation on approximately the line 3—3 of Fig. 2.

15 Fig. 4 is a section on approximately the line 4—4 of Fig. 3.

Fig. 5 is a section on approximately the line 5—5 of Fig. 3.

Fig. 6 is a section on approximately the line 6—6 of Fig. 3, and

20 Fig. 7 is a section on approximately the line 7—7 of Fig. 3.

As above stated, the invention will be described as embodied in a machine according to United States Patent 625,998, 25 and it is considered only necessary to refer briefly to the parts of that machine which co-operate directly with the mechanism of the present invention.

30 A, A¹, A², A³ (Fig. 4) are the motors of one series, B, B¹, B², B³ are the motors of the other series, C, C¹, C², C³ (Fig. 5) represent the four series of valves operated by the motors A, A¹, A², A³, and D, D¹, D², D³, are the four series of valves operated by the motors B, B¹, B², B³.

35 E, E¹ (Fig. 1) indicate the two series of gages or stops for determining under the action of the signals in the record strip, the positions of adjustment of the die case. F 40 is the tracker bar or cross girt over which the record strip is passed so that the perforations in the strip control the port openings in the bar. G, G¹ are the positioning mechanisms operated by cam mechanism 45 (not shown) and acting in conjunction with the gages E, E¹ to position the die case H over the mold J. The die case is furnished with a draw rod H¹ engaged by the mechanism G and the movable carrier H² of the die case has a draw rod H³ which is engaged by the mechanism G¹.

50 The extreme advance movement of the die case in its column and row selecting directions can be and is determined by fixed stops; hence it is unnecessary to provide signals in the pattern for such positions or air conduits leading to these two gage pins. Thus, for the column of characters along one side of the die case it will only be necessary to provide a perforation to select the particular matrix in the column, and, on the other hand, if the desired matrix is in one of the extreme rows, no perforations for that row will be required but only 55 one for the column in which the matrix is

located. Because of this it is not necessary to provide a punch for indicating one of the extreme columns, nor one for indicating one of the extreme rows, and the matrix at the intersecting point of this column and row, or in the zero position, requires no perforation at all.

70 The record strip is fed step by step over the cross bar or tracker bar F which is carried in a tower F¹ (Figs. 2, 3 and 4) and the strip passes between the bar F and a movable air bar F² which has a valve controlled air supply from which air passes through the openings or perforations in the record strip and thence to the air conduits 75 in the tracker bar.

80 In the machine as hitherto constructed the air conduits in the tracker bar lead direct to the gage pins E or E¹ and to the mechanism controlling the devices for setting the justification mechanisms.

85 According to the present invention however the air conduits in the tracer bar F with the exception of those for the justifiable space and the justification setting devices, lead to the two series of motors A, A¹, A², A³, and B, B¹, B², B³.

90 The piston or pistons of the motor or motors energized by air passing through the perforations in the record strip lift the valves, bars, or levers, allotted to it or them, and when a valve lever is thus lifted all the valves of the particular series are 95 opened. Owing to the arrangement of the intercommunicating conduits between the valves, however, air only passes to a stop pin when the motor controlled valves in the air supply conduit thereof are simultaneously operated.

99 In the present embodiment, the tracker 105 bar F is furnished with eleven perforations, four of which f, f¹, f², f³ communicate with the motors of series B and another four f⁴, f⁵, f⁶, f⁷ communicate with the motors of series A, the perforation f⁸ is the 110 justifiable space perforation which leads to the existing device K (Fig. 1) on the machine and the perforations f⁹ and f¹⁰ controlling the justification setting devices lead to the justification devices indicated at L 115 L¹ (Fig. 1).

120 The motors A, A¹, A², A³, and B, B¹, B², B³ comprise cylinders respectively a and b formed in blocks a¹, b¹ which rest on plate a² b² in the base of the tower F¹ and which are furnished with air supply conduits a³ or b³ which communicate with pipes F², F³ leading from the openings in the tracker bar F.

125 There is one motor of the series A for each series of valves of the group C and one motor of the series B for each series of valves of the group D.

130 Conveniently these control valves are arranged in the two series A or B one for each

group of stop pins E E¹, and there are four rows of valves in each series, each row being operated by a separate motor. The constant or stop pin operating air supply has a conduit leading to each stop pin and the motor operated valves are located in these conduits. There may be from one to four of such valves in a conduit, and where there are more valves than one in a particular conduit, the air is led to the upper side of each valve and when this valve is opened, the air passes through and by a conduit enters the upper part of the chamber of the next valve in that conduit and so on.

For example, the piston *a* of the motor A has attached to or bearing upon the outer end of its piston rod a bar or lever A⁴, the ends of which are bent at right angles to the body of the bar and are fulcrumed on a rod or shaft M. Bearing upon this bar or in position to be operated by it, are the stems of the valves in the group C. Similarly the motors A¹, A² and A³ operate bars A⁵, A⁶ and A⁷ respectively, each of which bars are adapted to actuate a series of valves respectively of the groups C¹, C² and C³.

The valves C, C¹, C² and C³ are formed in a block C¹⁰ which is placed over the motors A, A¹, A², and A³. In the embodiment illustrated, there are eight valves in each group. In the group C the valves *c*, *c*¹, *c*², *c*³, *c*⁴, *c*⁵, *c*⁶ and *c*⁷ have stems C⁴ which project through the lower surface of the valve chamber and rest upon the bar A⁴ operated by the motor A. The valves *c*⁸, *c*⁹, *c*¹⁰, *c*¹¹, *c*¹², *c*¹³, *c*¹⁴ and *c*¹⁵ of the group C¹ have stems C⁵ which rest on the bar A⁵ operated by the motor A¹, the valves, *c*¹⁶, *c*¹⁷, *c*¹⁸, *c*¹⁹, *c*²⁰, *c*²¹, *c*²² and *c*²³ of the group C² have stems C⁶ which rest on the bar A⁶ operated by the motor A², and the valves *c*²⁴, *c*²⁵, *c*²⁶, *c*²⁷, *c*²⁸, *c*²⁹, *c*³⁰ and *c*³¹ have stems C⁷ which rest upon the bar A⁷ operated by the motor A³. Each of these valves is maintained in its closed position by a spring C¹¹. All the valves of the groups C, C¹, C² and C³ have a common air supply which enters from a supply pipe C¹³ into a channel C¹² (Fig. 1) from which are lead conduits *e*, *e*¹, *e*², *e*³, *e*⁴, *e*⁵, *e*⁶, *e*⁷, *e*⁸, *e*⁹, *e*¹⁰, *e*¹¹, *e*¹², *e*¹³ and *e*¹⁴, each of which conduits is controlled by a valve in one or more of the groups C, C¹, C² and C³ and beyond the valves these conduits lead to the motors of the gage pins of the series E.

Stop or gage pin No. 1 of group E is a fixture and as stated requires no motor or perforation in the record strip to control it.

In the conduit *e* which leads to the pin No. 2 there is only the valve *c* of the group C; in the conduit *e*¹ which leads to pin No. 3 is the valve *c*⁸ of the group C¹; in the conduit *e*² which leads to pin No. 4 are the valves *c*¹ of the group C and *c*⁹ of the group C¹; in the conduit *e*³ which leads to pin No.

5 is the valve *c*¹⁶ of the group C²; in the conduit *e*⁴ which leads to pin No. 6 are the valves *c*² of the group C, and *c*¹⁷ of the group C²; in the conduit *e*⁵ which leads to pin No. 7 are the valves *c*¹⁰ of group C¹ and *c*¹⁸ of group C²; in the conduit *e*⁶ which leads to pin No. 8 are the valves *c*³ of group C, *c*¹¹ of group C¹ and *c*¹⁹ of group C²; in the conduit *e*⁷ which leads to pin No. 9 is the valve *c*²⁴ of group C³; in the conduit *e*⁸ which leads to pin No. 10 are the valves *c*⁴ of group C and *c*²⁵ of group C³; in the conduit *e*⁹ which leads to pin No. 11 are the valves *c*¹² of group C¹ and *c*²⁶ of group C³; in the conduit *e*¹⁰ which leads to pin No. 12 are the valves *c*⁵ of group C, *c*¹³ of group C¹ and *c*²⁷ of group C³; in the conduit *e*¹¹ which leads to pin No. 13 are the valves *c*²⁰ of group C² and *c*²⁸ of group C³; in the conduit *e*¹² which leads to pin No. 14 are the valves *c*⁶ of group C, *c*²¹ of group C² and *c*²⁹ of group C³; in the conduit *e*¹³ which leads to pin No. 15 are the valves *c*¹⁴ of group C¹, *c*²² of group C² and *c*³⁰ of group C³ and in the conduit *e*¹⁴ are the valves *c*⁷ of group C, *c*¹⁵ of group C¹, *c*²³ of group C² and *c*³¹ of group C³. The conduit *e*¹⁴ will not be used in the machine as hitherto constructed as there is no gage pin for it in the series E, but a pin may be provided making provision for positioning a larger die case than at present in use.

Similarly with the motors B, B¹, B² and B³, and the valves of the groups D, D¹, D² and D³. The motors B are similar in construction to those above described, they are in communication with openings in the cross bar F by pipes F³ and conduits B³ and are adapted to operate bars B⁴, B⁵, B⁶ and B⁷ which are hinged on a rod or shaft M¹. The valves of the groups D, D¹, D² and D³ are similar to the valves already described and are arranged in a similar manner. A constant supply of air is led into a chamber B¹⁰, from which lead conduits *e*¹⁵, *e*¹⁶, *e*¹⁷, *e*¹⁸, *e*¹⁹, *e*²⁰, *e*²¹, *e*²², *e*²³, *e*²⁴, *e*²⁵, *e*²⁶, *e*²⁷, *e*²⁸ and *e*²⁹.

Beyond the valves the conduits lead to the gage pins of series E¹. Pin No. 1 is a fixture and no conduit leads to it. In the conduit *e*¹⁵ which leads to pin No. 2 is the valve *d* of group D, in the conduit *e*¹⁶ which leads to pin No. 3 is the valve *d*⁸ of group D¹, in the conduit *e*¹⁷ which leads to pin No. 4 are the valves *d*¹ of group D and *d*⁹ of group D¹, in the conduit *e*¹⁸ which leads to pin No. 5 is the valve *d*¹⁶ of group D², in the conduit *e*¹⁹ which leads to pin No. 6 are the valves *d*² of group D and *d*¹⁷ of group D², in the conduit *e*²⁰ which leads to pin No. 7 are the valves *d*¹⁰ of group D¹ and *d*¹⁸ of group D², in the conduit *e*²¹ which leads to pin No. 8 are the valves *d*³ of group D, *d*¹¹ of group D¹ and *d*¹⁹ of group D², in the conduit *e*²² which leads to pin No. 9 is the valve *d*²⁴ of group

D³, in the conduit e²³ which leads to pin No. 10 are the valves d⁴ of group D and d²⁵ of group D³, in the conduit e²⁴ which leads to pin No. 11 are the valves d¹² of group D¹ and d²⁶ of group D³, in the conduit e²⁵ which leads to pin No. 12 are the valves d⁵ of group D, d¹³ of group D¹, and d²⁷ of group D³, in the conduit e²⁶ which leads to pin No. 13 are the valves d²⁰ of group D² and d²⁸ of group D³, in the conduit e²⁷ which leads to pin No. 14 are the valves d⁶ of group D, d²¹ of group D² and d²⁹ of group D³, in the conduit e²⁸ are the valves d¹⁴ of group D¹, d²² of group D² and d²⁰ of group D³ and in the conduit e²⁹ are valves d⁷ of group D, d¹⁵ of group D¹, d²³ of group D² and d³¹ of group D³. Conduit e²⁹ does not lead to any gage pin in the machine, as at present constructed, but can be used with an additional gage pin to provide an additional adjustment of a larger die case.

In some instances with the above described mechanism, while only one stop pin of a series is required to be projected, two or more pins will actually be projected: for example, when the fourth stop pin of series E is required, the motors A and A¹ will be energized, and all the valves of groups C and C¹ will be operated. This allows air to pass to the second stop pin as it is controlled only by the valve c situated in the group C. Similarly the third pin controlled only by the valve c⁸ in the group C¹ will also be operated; while the fourth pin, the one required, being controlled by two valves, one c¹ in group C and c⁹ in group C¹, will likewise be projected. This operation of stop pins does not interfere with the accurate positioning of the die case, because of the pair of positioning jaws which co-operate with the stop pins E, that one which actually contacts with the pins advances from be-

yond the fifteenth stop pin towards the fourth and therefore will contact first with the fourth pin in the present example, while the co-operating jaw does not actually contact with the pins Nos. 1, 2 or 3, but will pass over them until it is arrested by striking against the complementary jaw which has been arrested by the fourth pin.

The invention has been described as embodied in a known machine and co-operating with the die case positioning mechanism of such machine. It is to be understood however that the invention is not restricted to its application to this machine, as it is applicable to other forms of positioning mechanisms or type composing machines of widely different constructions.

I claim:

1. In an automatic or record strip controlled type casting machine, the combination with a series of gaging devices, of control valves therefor arranged in separate series, with intercommunicating conduits, and a separate signal responsive motor for each series of valves.

2. In an automatic or record strip controlled type casting machine the combination with a series of positioning gages of a number of separate signal responsive motors, a series of valves controlled by each motor and conduits between the series of valves and between the valves and the positioning gages.

3. In an automatic or record strip controlled type casting machine, the combination with a series of positioning gages, of control valves therefor arranged in series with intercommunicating conduits, a series of separate signal controlled motors and a bar operated by each motor to operate simultaneously a series of the valves.

RICHARD CORNELIUS ELLIOTT.
